SCORE REGISTER

Adolf Holzner, Brooklyn, N. Y.

Application May 17, 1937, Serial No. 142,975

5 Claims. (Cl. 235—117)

This invention relates to improvements in counters, as they are for instance described in my co-pending application, Serial No. 690,811, filed September 25, 1933, in which a total and a separate score counter are coupled in such a manner that by the operation of a wheel to turn in one direction a score is set in both of the counters, while the operation of the wheel in the opposite direction will have no effect on the separate counter, which thus will remain stationary, while the total score counter will turn to act for subtraction.

It is the object of the present invention to improve the counter disclosed in my prior above identified application so as to provide a more perfect device which answers all requirements for keeping score of a pocket billiard game.

It is one of the objects of my present invention to couple three counters in such a manner as to indicate in one counter the scratches, in the other the total score, and in the third or separate counter the number of balls in innings played.

At the start of the total counter in one direction to count the score made, the scratch counter will remain stationary, while the total and the separate score counters will act to add the number of balls played.

If, however, the total score counter is operated to turn in the opposite direction, the scratch counter will act to add the scratches, while the total score counter acts for subtraction and the separate score counter will remain stationary.

Another object of my invention is the provision of a counter employing two operating members, one for subtraction and the other for adding whereby the operation of one of these members will be indicated by the sounding of a bell, and the operation of the other of these members will also be indicated by a bell however having a different tone than the first named bell, either of a higher or lower pitch.

It will be clear that in this manner the counter will attract the attention in a pleasing and attractive manner as the sounding of the bells will instantly call the attention of players as well as onlookers to the progress of the game.

It frequently happens in a game that one of the players has balls to subtract while he has no score balls made, and it is a further important object of my invention to provide a counter in which during the addition of the scratch balls while the total score counter is rotated also, the numbers 999 as they would appear in the counter

in the above identified patent application, are covered by a plate showing the numerals 000 and brought before the number wheels at the correct moment by a special mechanism, so that during the operation of the scratch counter the total counter can be operated without displaying the misleading numbers 999 in the total score counter.

A still further object of my invention is the provision of a counter of the duplex type in which in contradistinction to the cam operated slides disengaging the transfer shaft along longitudinal slots in the casing, as disclosed in my above mentioned prior application, in this application, I reduce the slides and use one cam to operate two slides, while in the present application I use one cam which operates one slide only, and thus simplify the construction considerably.

These and other objects and advantages of my invention will become more fully known as the description thereof proceeds, and will then be specifically defined in the appended claims.

In the accompanying drawing forming a material part of this disclosure:

Fig. 1 is a front view of a counter constructed according to my invention, with parts of the housing broken away to disclose the interior mechanism.

Fig. 2 is a section on line 2—2 of Figure 1.

30

Fig. 3 is a section on line 3—3 of Figure 1.

Fig. 4 shows a detail view of an operating wheel to impart a step by step motion to the first number wheel of the counter.

Fig. 5 is a detail view of a clutch.

35

Fig. 6 is a detail view of a spring-controlled ratchet wheel.

Fig. 7 is a section on line 7—7 of Figure 1.

40

Fig. 8 shows the mechanism illustrated in Figure 7 at an angle thereto.

Fig. 9 is an end view fragmentarily illustrating the spring controlled hoop-member.

45

As illustrated, the housing 1 of the counter constructed according to my invention is divided by the partitions 1a, 1b and 1c into four chambers containing the operating mechanism.

Between the partitions 1a and 1b a shaft 12 is located freely rotating in suitable bearings in these walls and carries the number wheel A in the chamber formed by the partition walls 1b 50 and 1c, and extends through partition wall 1c and carries on its outer end an operating wheel 17, which, as shown in Figure 4, has ten notches, and a spring 30 engages in one of these notches for a purpose later on more fully to be explained. 55

I will now first describe the transfer mechanism from one number wheel to the other:

- Number wheel B has a bushing 9 and said number wheel B is next to the number wheel A which rotates freely on shaft 12 and number wheel C has also a bushing 10 freely rotating on bushing 9 and the zero wheel Z rotates freely on bushing 10, while a gear 52 is secured to wheel Z and a gear 5c is secured to the bushing 10 of number wheel C, while a gear 5b is secured to bushing 9 of the number wheel B and a gear 5a is secured to the shaft 12 carrying number wheel A. These gears serve to set the number wheels to zero, as will later on more fully be described.
- Each of the number wheels has a finger disk 2 associated therewith and also a gear 3 with 10 teeth as shown in Figure 3, except the first number wheel A on the shaft 12 with which the gear 3 is replaced by a wheel 17 as above stated.
- A transfer shaft 25 (Fig. 3) is arranged behind the shaft 12 and is held by slides while bearing in slots of the casting walls as will be hereinafter more fully explained.

The transfer shaft 25 carries freely turning gears 28 having each six teeth, (Fig. 3), and a finger disc 2 is placed just in front of one tooth of gear 28, and if the number wheel A is rotated in a direction in which the numeral 1 follows upon 0, Fig. 1, downwardly, and Figure 3 anti-clockwise, the arrow shown in Figure 3, and pointing in clockwise direction is for the indication of the operation of the zero plate to be more fully explained hereafter the finger disk 2 will leave gear 28, and if this turning movement is continued until the numeral 9 appears, the finger disc 2 will assume a position in front of a tooth on gear 28, and upon further rotation of the number wheel A the disc 2 will come in mesh with gear 28 on shaft 25, and in this moment a transfer operation takes place over to the number wheel B which has a gear 3 in engagement with gear 28, as gear 28 is as wide as both the finger disk 2 and gear 3, so that by said operation the number 10 appears before the window, the numeral 1 on number wheel B and the numeral 0 on number wheel A, and in this manner a transfer operation from one number wheel to the other is effected.

The same operation will take place as aforementioned with respect to number wheels A, B and C on shaft 12, with number wheels A', B' with the exception that the numerals on wheels A', B' run in a direction opposite to the reading of the numerals on wheels A, B and C, and are naturally also operated in opposite direction, as for instance, upon the downwardly directed rotation of number wheel A on shaft 12, the numeral 1 follows upon numeral 0, while on number wheel A' on its shaft 11 in an upwardly directed rotation, numeral number 1 follows 0. In the scratch counter the finger discs 2' and gears 3' work in the same manner as described with respect to disks 2 and gears 3 for the total score counter with the exception that the finger disk 2' is not arranged above one tooth of gear 28 (Fig. 3), but below such a tooth so that by starting the operation of the scratch counter finger disk 2' will turn in a direction opposite to the clockwise rotation of disc 2.

Returning to the shaft 12 carrying the number wheels A, B and C and the zero wheel Z. This wheel Z and the zero plate 13z has the following purpose: It frequently happens that the player must subtract a ball while he has as yet no total score and the number wheels A, B and

C display the numerals 000, if now in the counter a subtraction must take place while all number wheels display a 0, as soon as the counter is operated, in a direction opposite to direction for adding the score, all number wheels A, B and C would show the numerals 999 and if further rotated they would display the numerals 998, and in order to avoid such display which would be erroneous and misleading, I have provided the zero wheel Z with a plate 13z as shown in Figure 3 which will cover the number wheels C, B and A and be spaced from said wheels to leave just room enough for the number wheels to move without being touched by plate 13z, and thus, if the number wheels are rotated to display the numerals 999 this number will be covered by the zero plate 13z carrying the three numerals 000, so that the counter can be further operated in the same direction, while the zero plate remains in position to cover the numerals on the counters A, B and C until the counter is again operated for adding purposes and subtraction as well, and the zero plate will disappear for instance with the first subtracting operation three 999 will appear behind the zero plate and at the second operation the numeral 998 and with the adding operation beneath plate 13z appears the numeral 999 and with the second operation disappears the zero plate and the three 000 of the number wheels appear. This mechanism operates in the following manner: As shown in Figure 3, the finger disks 2 of the number wheels A, B and C are located exactly in front of one tooth of the gears 28 and all of the gears 3 are in mesh with the gears 28 and also the gear 3 of the zero wheel Z, and with one operation of the number wheel A in a direction opposite to adding the score, the finger disk 2 of all the number wheels meshes with all of the gears 28 and a transfer from one number wheel to the other is effected and also to the zero wheel Z, which then moves upward with the zero plate 13z, or, as shown in Figure 3 by the arrow, in clockwise direction.

The zero plate 13z is made in one piece with the plate of wheel Z, bent at an angle thereto, as shown in Figures 1 and 3, and will display the three 000 behind the window and cover thereby the three 999 on the number wheels A, B and C, as above described. The aforescribed movements or operations of the zero plate are taking place as described because all the gears 3 of all the number wheels and the gear 3 of the zero wheel Z are in mesh with the gears 28, and also all the discs 2 of all the number wheels will periodically come into mesh with the same gears 28, so that by the operation of the first number wheel A in a direction opposite for adding, all the remaining number wheels and the zero wheel will be forced to move in the same direction, as indicated by the arrow in Figure 3, in clockwise direction, and in the illustration Figure 1, upwards. It will be understood that while Figure 3 shows one of the wheels 28 only, the one between the number wheel C and the zero wheel Z, other wheels 28 are also between the number wheels C and B and between B and A.

The springs 29 hold the gears 3 in position, and also hold respectively the number wheels in place and alignment.

For the purpose of quickly resetting the number wheels of two oppositely arranged counters the following mechanism is provided:

In the Figure 2 a section is shown taken through the operating mechanism for the number wheels A', B' on shaft 11 to show the man-

ner of resetting which is the same for all the number wheels. As shown in Figure 1, number wheel A' is secured to shaft 11, number wheel B' is freely rotating on shaft 11 and at its left side is provided with a gear 5d secured thereto and following the same a gear 5e is secured on shaft 11 belonging to number wheel A', and as shown in Figure 2, gear 5e has 8 teeth and a gap 63. A shaft 15 extending through the chamber in which the number wheels A, B and C are located, also extends through the chamber for numeral wheels A', B' on shaft 11, and a bushing 16 extending to the outside of the casing freely rotates on shaft 15 which also extends to the outside of the casing and said bushing 16 has secured thereto two cams 7 and one gear 8 which is as wide as the two gears 5e and 5d, and the gear 8 has also two gaps 64 on oppositely disposed faces. Figure 2 illustrates gear 5e of number wheel A' in zero position. If now after a counting operation it is desired to reset the number wheels, before this resetting the number wheel will display any of the numbers except 0, and the gap 63 will have assumed a position at any point along the circumference of the gear 5e, and thus a tooth has to be at that point, where the gap 63 used to be when the number wheel displayed 0. Now, by turning the bushing 16 downwards for instance by a knurled collar, as provided in my Patent No. 2,097,065, the gear 8 will engage a tooth of gear 5e and turn the same until the gap 63 assumes its position in alignment with the center line of the bushing 16, and the number wheel is zeroized. If now the rotation is continued, the gear 8 will always turn idly in the gap 63 and therefor the number wheel will be zeroized in one revolution of bushing 16 and gear 8, because gear 8 is secured to the bushing 16, and gear 8 has eight teeth and two gaps 64 and there are just as many teeth as on gear 5e. The gaps 64 on gear 8 serve the purpose of allowing the gears 5c of the two opposite counters, one for each player, to pass without meshing with the same during the counting operation.

The same operation is performed by number wheels A, B and C and the zero wheel Z on shaft 12, each of these number wheels has a gear 5 and also the zero wheel Z, the gear 8' on the shaft 15 is as wide as the gears 5a, 5b, 5c and 5z. To make it possible that before said resetting operation can take place in all of the counters, the gears 28 on shaft 25 must be uncoupled from the gears 3 and finger disks 2 and for this purpose the slide 6 and the cams 7 are arranged.

Two transfer shafts of two oppositely disposed counters bear in the slides 6 and the projecting ends of shafts 25 are displaceable within the slots 26 in the casing. The slides are displaceable and have two slots 27 through which spindles 11 of the counters A', B' and 12 of the counters A, B and C extend. The cams 7 have the cam faces 7a and the slides are pressed against the cam faces 7a by the springs 24.

By turning the bushing 16 and shaft 15 downwards for zeroizing the number wheels A, B and C, the cams 7 will press against the slides and move the same, and the machine must be timed so that before engaging gear 8 with gear 5 the cams uncouple the gears 3 and finger disks 2 and no jamming of the mechanism can take place.

As shown in Figure 1, a shaft 14 carries number wheels A'' and B'' and it is believed their operation need not further be described as the operation of the same by the transfer mechanism and the zeroizing remains the same as above de-

scribed with respect with the other number wheels.

In the upper part of the casing three counters are provided having number wheels 56 which are necessary to perform the operations mentioned in the practical examples at the end of this description. All number wheels 56 are freely rotating on a shaft and each of these number wheels has an operating wheel 55 which operates just as wheel 17 Figure 4 only it is of a larger size and projects through an opening in the casing so that the operator can manipulate it. This wheel 55 has also ten notches and a spring the same as stated above with respect to wheel 17 (Fig. 4) engaging in one of these notches.

After having thus described the transfer and zeroizing mechanism I will now describe the specific manner of coupling the counters with one another.

We have here three spindles which carry number wheels, spindles 11, 12 and 14, and the coupling and operation is effected in the following manner: Counter A, B, C, when so turned that the number wheels rotate in adding direction, will simultaneously have counters B'', A'' participate in this adding operation and the operation takes place at the point where both spindles 12 and 14 meet with their ends. During this operation the counter A', B' remains stationary. The next operation when counter A, B, and C is operated to turn the number wheels for subtraction, it will simultaneously operate counter A', B', the wheels whereof however will operate for adding the score, and the operation takes place at the point where the ends of the spindles 11 and 12 meet, and during this operation the counter A'', B'' will remain stationary. The mechanism during this operation will operate in the following manner: If counter A, B, C, is operated to subtract, spindles 12 and 11 each of which has a ratchet wheel 32 attached thereto and also other ratchet wheels R on spindle 14, R' on spindle 11, R'' on spindle 15, R''' on spindle 16, and R'''' on shaft 65 will be allowed to operate in upward direction only as a spring 62 (Fig. 6) engages the ratchet wheel R. The means for the operation of the two counters or the two ratchet wheels 32 are the following: If operating member or button 22 is pushed, a substantially U-shaped member 33 will be operated as the member 22 is secured to a shaft 48 which is guided in an opening of the casing and is secured to member 33 which has curved shape and carries at its lower end a pin substantially square in cross-section, designated 35 while shaft 48 is secured to the loop member 33. The cross-pin 35 is guided within a guide 37 provided with a square opening, while shaft 35 has at one end a round portion 54. The guide member 37 is riveted to the casing and a plate or disk rests upon the rivets 60 while a coil spring 36 rests on this plate and another plate 51 is provided on the lower part of the loop member 33 and presses the coil spring 36 together if the operating member 22 is pushed so that loop member 33 is raised again for a new operation. With the depression of member 22, the spindles 11 and 12 are rotated, and a hook 34 which is as wide as the two ratchet wheels 32 and pivoted about a pin 49 which is secured to the loop member 33 is adapted to enter 70 with play a recess 53 in the member 33 and rotates freely on pin 49 while a spring 47 secured to the loop 33 presses the hook 34 normally into this recess. Upon depression of the member 22 and loop 33 the hook will engage one tooth of the 75

- ratchet 32 and take it along up to the horizontal center line in which case the hook is pressed against the action of spring 47, and in the same moment the spring 62 will engage another tooth of the ratchet wheel R and prevent the shaft 11 to turn in the opposite direction, while upon the upward movement of the loop the coil spring 36 will return the loop into its elevated original position upwardly, so that the hook 34 glides along a surface 32a and will thus be unable to turn the ratchets 32 into the position originally held as the spring 62 as mentioned above, now holds or arrests the ratchet wheel R and thus also ratchet wheel 32 of spindle 11 so that also the ratchet wheel 32 on spindle 12 cannot be returned or taken along into its prior position, as the hook 34 glides along the surface 32a of the ratchet 32 on shaft 11 and during upward movement cannot exert any pressure on the ratchet 32 on shaft 12 in order to take it along. In this moment during the upward movement of the loop 33 the spring 47 presses the hook 34 again into its prior position in which it is located in front of a tooth of ratchet 32.
- 26 The same is true with respect to the operating member 23 for counters A'' and B'', with the operating member 22 actuated as described with the exception, that the ratchet wheels 32 and R on shaft 14 have their teeth directed in opposite direction so that upon an adding operation of spindle 12 also spindle 14 will be operated for adding. The same operation as described with respect to the member 22 and ratchet wheel R is taking place with respect to ratchet wheel R on the shaft 14.
- 27 It will be evident that the members 22 and 23 are eccentrically located on the shafts 48 in order to give the counter a more pleasing appearance because the members are thus located in the center between the two counters, although shaft 48 is closer to one counter than to the other.
- 28 As seen in Figure 1, operating member 22 is designated by the legend "Sub" and member 23 by the legend "Add," for subtracting and adding respectively, and the depression of both produces the above described operations and simultaneously with these operations a bell is sounded which operates in the following manner:
- 29 On the rear wall of the casing a square post 48 is provided having one of its ends threaded and extending into the casing and carries there a nut 39 which holds the post to the casing. This post has a space 46 formed therein (Fig. 7) in which move two lever arms 43 and 44 pivoted on a pin 42 secured to the post 48. At the end of the post the same has a reduced part 41 on which the bell 50 is secured. As shown the arms 43, 44 are suitably bent and carry at their ends small balls K and K'. To the post 48 are secured two coil springs 39 one for each arm which are also secured to the arms 43, 44. If now member 22 is depressed, the round portions 54 at the end of the shaft 35 will press upon the arm 43 so that its end will be lowered and the other end of 43 with the ball K will be removed from the bell 50 while during the upward movement of shaft 35 the coil spring 39' will return arm 43 into its prior position and in this moment the ball K' will strike the bell and produce a sound. It will be understood that each pair of the operating knobs 22 and 23 operates a different bell 50, only one of which is shown as an example, and it will be understood that the bell not shown 75 differs from that shown in tone only so that the

description of one bell will also describe the construction of the other and its cooperating parts and operation of same. The operating knob 23 operates the bell 50 to indicate addition, and the operating knob 22 operates for subtraction in one counter and addition in the other.

As it is desirable to produce two different tones by the operation of member 22 one to indicate subtraction, and for 23 to indicate addition, or if so desired, one of the bells 50 is made of thicker material than the other, or one of the balls K on the arms 43 and 44 is thicker than the other.

If it is desired to use an operating wheel as it has been described in my above identified pending application, Serial No. 690,811, a coupling as shown in Figure 5 is used. As shown there, the shaft 12 carries a coupling member 18 and the shaft 14 carries a pin 20 engaging the groove in the coupling member 19 while a coil spring 21 holds the coupling members in engagement with one another. A like coupling is provided on shaft 11 and the other end of shaft 12 only in the reversed order to the illustration in Figure 5. With these couplings the three counters can be coupled respectively in the following manner: by turning wheel 17 which is just as large as wheel 55 of said patent application, so that the operation can be effected from outside of the casing. Upon the downward rotation of wheel 17 (Fig. 1) counters A'', B'', and A, B and C will operate to add the score and counter A'' B'' remains stationary because member 18 of the coupling on spindle 12 when coupled to member 19 on spindle 14 will cause operations of both shafts 12 and 14 to operate simultaneously and in the same direction, 25 while coupling member 18 is separate from member 19 on the shafts 11 and 12 respectively, and thus the ratchet wheel R on shaft 11 will arrest member 18 and prevent the same from turning in the direction of rotation of shaft 12. Upon upward rotation of wheel 17 counter A'' B'' will remain stationary, counter A, B, C subtracts and counter A'B' adds the score, because member 19 on spindle 14 will slide off member 18 on spindle 12 because a ratchet wheel R on the spindle 14 prevents it to rotate in this direction and member 19 at the other end of the shaft 12 will take along member 18 on spindle 11 as the ratchet R on spindle 11 will allow its rotation in the aforementioned direction.

The counters are zeroized in a direction as permitted by the respective ratchet wheels R and a ratchet wheel R is on bushing 16, shaft 15 and shaft 65 and prevents that shaft 15 and shaft 65 and bushing 16 be turned in an opposite direction.

In the practical operation of my counter, if for instance two players agree to play a game for a total score of 125 balls, the counter works in the following manner:

The upper counters on spindles 11, 12 and 14 count the balls for the first player, and the lower counters 11a, 12a and 14a count the balls for the second player, each player has two operating members 22 and 23 at his disposal.

Now, assumed, the first player counts his high run in the upper left counter D and the second player counts his high run in the upper right hand counter E, and the upper counter F between the left and right hand counter counts the 70 innings, and when the play begins the inning counter is operated for showing the number 1 to indicate the start of the first inning: If now the first player shoots 8 balls off the table, and while shooting the ninth predetermined or designated 75

ball, he hits the ball, but does not succeed to drive the ball into the predetermined or designated pocket of the table, and the second player will now start his game, the first player will now 5 count his score balls by pressing member 23 eight times so that the counter on spindle 11 will remain in zero position, while the counters on spindles 12 and 14 will show the number 8.

The second player at the start will, it is assumed, hit the predetermined or designated ball, but his white or play ball runs into one of the pockets and must be counted as a scratch ball, the player will then have to press member 22, so that the counter 11a shows the number 1, while 10 counter 12a on account of the aforescribed mechanism will have the plate with the zeros thereon in front of its number wheels, and the counter 14a remains stationary. In the meantime the first player whose high score was 8 will 15 operate the operating wheel 55 in the upper left hand corner counter D until the number 8 appears thereon.

If now the first player starts in again, the second inning begins, and the inning counter will 20 be operated to show the number 2, and also the inning run counter on spindle 14 and counter 14a will be operated for zeroizing by turning the shaft 65, so that the counter or register shows:

30   08   02   00
          00   008   00
          01   000   00

If now the first player shoots 16 balls off the 35 table, and while aiming at the 17th ball misses the predetermined ball, which means he will have to subtract one from his total, he presses to this purpose member 23 16 times and the counter on spindle 11 on account of the aforescribed mechanism will remain stationary, 40 while the counter on the spindle 12 shows the number 24 and the counter on the spindle 14 shows 16, the player will then operate member 22, so that counter on the spindle 11 will show 1, the counter on the spindle 12 will subtract and 45 show 23 and counter on spindle 14 will remain stationary and show the number 16.

Assumed the second player starts now to play again, and misses this time the predetermined ball which will necessitate another operation of member 22 so that counter 11a shows 2 and in counter 12a the 0 on the zero plate will remain stationary and also counter 14a will remain so.

Thus the second inning is over and the third inning starts, the inning counter will be operated to show numeral 3.

The first player keeping in mind his highest score in an inning, and by operating the counter in the left hand corner the number 16 will appear, and the counters on the spindle 14 and counter 14a will be zeroized by shaft 65, so that the register shows:

60   16   03   00
          01   023   00
          02   000   00

If then the first player shoots 35 balls off the table, he counts the score by pressing member 23 35 times so that the register shows:

70   16   03   00
          01   058   35
          02   000   00

If now the second player in this inning shoots this time 41 balls off the table, he will operate member 23 41 times, and the counter 11a remains

to show 2 counter 12a will show 39 and counter 14a will display the numeral 41, thus:

18   03   00
01   058   35
02   039   41

5

If now the fourth inning starts, the inning counter will be operated to show 4.

The first player has operated his high run counter to 35 and the second player his high run 10 counter to 41. Then the counters on spindle 14 and counter 14a again will be zeroized so that the register shows:

35   04   41   15
01   058   00
02   039   00

Beginning the fourth inning, the first player shoots 6 balls off the table and while the second player shoots 19 balls off the table but while aiming at the predetermined ball, he shoots his white or play ball also in one of the pockets and he must therefore operate member 23 19 times and member 22 once, so that the register shows:

25   35   04   41
          01   064   06
          03   057   19

Before the beginning of the fifth inning, the 30 inning counter is operated to show 5, and the counter on spindle 14 and counter 14a will be zeroized. No player operates the high run counter at this time. Thus the register will show:

35   05   41   35
01   064   00
03   057   00

The play is now continued, until in one counter on the spindle 12 and in counter 12a the number 125 will appear, and the respective player will 40 have won the game.

It is the rule of the game that 15 balls are placed upon the table, and all are to be played off with the exception of one single ball which remains in its place, while the other balls which have been shot off are placed again upon the 45 table in a triangular frame.

It is believed that from the above described operations the construction and operation of my register will be fully understood especially when having simultaneous reference to the drawing.

It will be understood that I have described and shown the preferred form of my apparatus as one example only of the many possible ways to practically construct the same, and that I may 55 make such changes in the general arrangement of the apparatus and in the construction of its minor details as come within the scope of the appended claims without departure from the spirit of my invention and the principles involved.

Thus, while my counter is specifically intended for keeping score, I desire to reserve my right to make the counter serviceable for any other purpose where three counters are employed to 65 keep certain records or the like.

Having thus described my invention, what I claim as new, and desire to secure by Letters Patent is:

1. A score keeper of the character described, 70 including a counter for total score, a counter for separate score, means to couple the total and separate score counters, and comprising a third counter, each of said three counters including a transfer mechanism, operating means to operate 75

the total and separate score counters in one direction for adding in both of these counters while the third counter remains stationary, means to operate the total score counter in opposite direction for subtraction, means to couple the total score counter and the third counter during the subtraction operation with the separate score counter uncoupled and remaining stationary, and a means actuated by the transfer mechanism 5 when starting the counting operation in the total score counter for subtraction to cover the number of wheels of the total score counter during the operation of the third counter for adding.

2. In a counter including operating means to start an adding operation when operated in one direction and to start a subtracting operation when operated to turn in the opposite direction, a plate displaying 0's to cover all the number wheels, and means to bring said plate into position in front of the number wheels to cover the numbers on said number wheels during a subtracting operation if the number wheels all display zeros at the beginning of said subtracting operation, and means to hold the plate in this 25 position until the number wheels again occupy zero position and are ready for adding the score.

3. A device including a total score counter, a separate score counter and a third counter, a means for producing subtraction in the total score counter and addition in the third counter while the separate score counter remains stationary, and comprising a housing having openings, operating members for the respective counters having each a specially designed or marked operating button protruding through the openings in said casing, a ratchet coupling for each oper-

ating member, a hook member on each coupling movably secured to its respective operating member, and springs to hold said hook member in engagement with said ratchet during counting in the total score counter and the separate score counter and during subtraction in the total score counter and addition in the third counter, other ratchet wheels on the respective counter spindles to prevent a rotation of the number wheels of the separate score counter during subtraction in the total score counter and a rotation of the number wheels of the third counter during addition in the total score counter and separate score counter.

4. In a score register including a total, separate and an extra counter, a zero plate for the total score counter so arranged that at the start of the operation of the first operating member, said zero plate appears before the total score counter, while upon the number wheels of said counter the numerals 999 appear beneath the zero plate, and during addition in the extra counter, while upon the operation of the second operating member said zero plate disappears again and the separate score counter starts for adding.

5. In a score register, as described, and including a total, a separate and a third score counter, a zero plate for the total score counter to cover the numbers of the number wheels, while the third counter operates for adding and the separate score counter remains stationary, while upon the starting of the separate score counter for adding the zero plate disappears again, and the third counter remains stationary.

ADOLF HOLZNER.
